UNITED STATES PATENT OFFICE

2,457,471

CHIMNEY CONSTRUCTION

Ernest O. Howle, Chicago, Ill.

Application December 5, 1945, Serial No. 632,864

4 Claims. (Cl. 72—94)

1

The present invention relates to a chimney construction, and particularly to one for use in carrying away the products of combustion from intermittently fired heaters, and has for its principal object means for preventing condensation of the products of combustion.

An object of the present invention is to provide a chimney construction wherein the products of combustion are prevented from condensing and wherein the stack temperature is maintained at a high level.

The present invention will be readily understood from the following description and accompanying drawing.

Fig. 1 is a vertical sectional view of a chimney constructed in accordance with the principles of the present invention;

Fig. 2 is a top line view of the chimney; and

Fig. 3 is a fragmental elevational view of the lower end of the chimney.

The chimney comprises an outer casing 5 of brick or the like, and defining an inner passage way 6 from the bottom to the top of the brickwork. This space is lined with a metallic liner 7 which extends from the bottom to the top of the brickwork.

Inwardly spaced from the liner 7, is the flue designated generally as A, and shown as comprising a plurality of sections of vitrified enameled metal arranged one on top of another, the sections being provided with modified bell and spigot joints for assembling the flue in stack formation.

The lower section 8 has a bottom 10 and a lateral take-off 11 which projects through a suitable opening in the brickwork whereby a heater may be connected to the flue. A drain pipe 12 leads from the lower portion of the interior of the section 8 through the brick wall for connection to the sewer.

The other sections 9 are all similar.

The upper end of the chimney is closed by a cap 13 which is made preferably of cementitious material supported on a hanger 14 suspended from the upper end of the liner 7, and surrounding the upper end of the flue.

The construction is such that a space 15 of substantial amount is provided between the flue A and the liner 7.

The liner 7 is made of a relatively thin metal which does not absorb heat to any considerable extent.

The space 15 between the flue and the liner is filled with finely ground aluminum silicate, which is a heat insulator.

2

The fact that the temperature of the flue is insulated from the brickwork 5 by the insulated space 15 means that very little heat escapes through the liner 7 to the brickwork. Whatever heat does escape is absorbed by the brick.

Inasmuch, therefore, as the heat escaping from the flue is not absorbed by the surrounding brickwork or the like, the temperature within the flue is maintained at a point sufficiently high to prevent condensation of the products of combustion. In other words, the temperature of the gases of combustion escaping through the top of the flue is much higher than it would be if the flue were encased by brick or some other absorbent material.

It has been found that a chimney of the character of the present invention, when used for intermittently fired heaters, creates a stack temperature of more than sufficient amount to vaporize the products of combustion and carry away such vaporized products as gas to the atmosphere.

It will thus be noted that a chimney constructed as herein described maintains the flue gases at temperatures in excess of the condensation temperatures of the gases, so that at all times the gases are prevented from condensing.

The drain 12 is provided to enable any rain water that might enter the top of the flue to drain off into the sewer.

It has been found that should moisture accumulate in the lower end of the flue, occasioned by rain water, melting snow or the like, the next time the heater is operated, the moisture will be quickly condensed and carried away to the atmosphere.

The brick chimney 5, or a chimney constructed of other suitable material, is heat resistant so that the major portion of the heat created within the casing 7 is transmitted to the flue, thus maintaining the temperatures of the flue gases at high points.

The invention is claimed as follows:

- 45 1. Chimney construction including a casing of brick or the like, a non-heat absorbent liner for the casing, a metallic flue spaced from the said liner and arranged with its lower end above the lower end of the casing, said flue having a closed bottom, a take-off for connection to a heater extending laterally from the flue and through the casing, and a filler of finely ground aluminum silicate below the lower end of the flue and occupying all of the space between the bottom of the casing and the lower end of the

flue and all of the space between the flue and said casing liner.

2. Chimney construction including a casing of brick or the like, a non-heat absorbent liner for the casing, a metallic flue spaced from the said liner and arranged with its lower end above the lower end of the casing, said flue having a closed bottom, a take-off for connection to a heater extending laterally from the flue and through the casing, a filler of finely ground aluminum silicate below the lower end of the flue and occupying all of the space between the bottom of the casing and the lower end of the flue and all of the space between the flue and said casing liner, and a cap of cementitious material overlying the upper end of the casing and surrounding the upper end of the flue, a portion of said cap resting on the upper end of the liner.

3. A chimney construction including a casing of brick or the like, a non-heat absorbent liner for the casing, a metallic flue spaced from said liner and arranged with its lower end terminating above the lower end of the casing, said flue having a closed bottom and having a lateral take-off for connection to a heater, and a filler of insulating material such as aluminum silicate the space below and around the bottom of the flue and between the flue and the liner.

4. A chimney construction including a casing of brick or the like, a non-heat absorbent liner for the casing, a metallic flue within said casing and having a lateral connection for a heater, the bottom of said flue being spaced above the bottom of the casing, and fine particles of an insulating material such as aluminum silicate occupying all of the space about the flue from the top of said liner to the bottom of the casing.
